CATTLE FEEDER

Charles R. Hesselman, Salina, Darwin L. Sampson and Vernon K. Smith, Wichita, and Jesse V. Downs, Salina, Kans., assignors to Grain Belt Supply Co., Inc., Salina, Kans., a corporation of Kansas

Filed Nov. 4, 1964, Ser. No. 82,466

Term of patent 14 years

(Cl. D12—2)

Fig.1.

Fig.2.

Fig.3.

Fig. 5.

Fig. 4.

FIG. 1 is a side elevational view of a cattle feeder, showing our new design;

FIG. 2 is an elevational view of one end thereof;

FIG. 3 is a sectional view taken on line 3—3 of FIG. 1;

FIG. 4 is a top plan view thereof; and

FIG. 5 is a perspective view thereof.

The side opposite to that shown in FIG. 1 and the end opposite to that shown in FIG. 2 are identical in appearance to the side and end shown, respectively.

We claim:

The ornamental design for a cattle feeder, as shown and described.
